UNITED STATES PATENT OFFICE.

THOMAS P. GREGER, OF PHILADELPHIA, PENNSYLVANIA.

DESIGN FOR A MANHOLE-COVER.

SPECIFICATION forming part of Design No. 30,696, dated May 2, 1899.

Application filed April 6, 1899. Serial No. 712,023. Term of patent 14 years.

To all whom it may concern:

Be it known that I, THOMAS P. GREGER, a citizen of the United States, residing at the city of Philadelphia, in the county of Philadelphia and State of Pennsylvania, have invented and produced a new and original Design for a Manhole-Cover, of which the following is a specification, reference being had to the accompanying drawings, forming a part thereof, in which—

Figure 1 is a top or plan view of a manhole-cover embodying my design, and Fig. 2 is a cross-sectional view of Fig. 1, these two views being deemed essential or necessary for the proper illustration and understanding of the design of my invention.

The leading feature of my present design consists of the configuration or outline of the cover in conjunction with the shape or form of the ornamentalations within the field of the cover.

Referring to the drawings, the cover when viewed in plan and section presents the appearance of a circular convex field *a*, sur-

rounded by a wall *b*, the interior surface of which is concaved, and the said wall thickened inwardly toward the top *b'*, so that an overhanging inner edge *b''* is formed, as illustrated in Fig. 2.

c represents a series of ring-shaped ornaments extending upwardly from the field *a* of the cover and the opening of each of which is of less diameter at the top than at the base, viewed from the under side of the bottom *a'* of the cover—that is, made tapering, as clearly illustrated in Fig. 2.

Having thus described my invention, what I claim as new, and desire to secure by Letters Patent, is—

The design for a manhole-cover, substantially as herein shown and described.

In testimony whereof I have hereunto set my signature in the presence of two subscribing witnesses.

THOMAS P. GREGER.

Witnesses:

J. WALTER DOUGLASS,
THOMAS M. SMITH.
